UNITED STATES PATENT OFFICE

136,466

DESIGN FOR A PIN OR SIMILAR ARTICLE OF JEWELRY

Emma T. Lee, Utica, N. Y.

Application October 16, 1942, Serial No. 108,536

Term of patent 3½ years

To all whom it may concern:

Be it known that I, Emma T. Lee, a citizen of the United States of America, residing at Utica, county of Oneida and State of New York, have invented a new, original, and ornamental Design for a Pin or Similar Article of Jewelry, of which the following is a specification, reference being had to the accompanying drawing, forming a part thereof, wherein:

I claim:

The ornamental design for a pin or similar article of jewelry, as shown.

EMMA T. LEE.
